(57) **CLAIM**

The ornamental design for a taillight emblem, as shown and described.

DESCRIPTION

FIG. 1 is a side view of a taillight emblem showing our new design positioned in a vehicle taillight assembly;

FIG. 2 is a front perspective view of the taillight emblem of FIG. 1;

FIG. 3 is a right elevated front view of a taillight emblem;

FIG. 4 is a front view thereof;

FIG. 5 is a side view thereof;

FIG. 6 is a top plan view thereof; and,

FIG. 7 is a left front elevated view thereof.

It will be understood that the dashed lines presented in the drawings are for illustration only, and do not form a part of the claimed design.
